DEFENSIVE PUBLICATION

UNITED STATES PATENT OFFICE

Published at the request of the applicant or owner in accordance with the Notice of Dec. 16, 1969, 369 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

U.S. Cl. 444—1
14 Sheets Drawing. 37 Pages Specification

To evaluate computer system performance, software techniques are frequently used to collect data on the system as it runs, and/or to simulate new devices. However, data collecting, simulating and report writing procedures degrade the performance of the system on which they are run and therefore provide distorted results. The technique herein is designed to hide the overhead procedure from the performance of the system by using prior art procedures in stopping the system clock whenever an overhead program is being executed, and adding to that a technique for compensating for distortion in the I/O area by intercepting and rescheduling I/O interrupts to compensate for the "stolen" time during which the system clock is stopped, and further delaying the scheduling of the I/O operation to compensate for changes in position of rotating peripheral devices during the "stolen" period.

The procedure involves the determination of the actual position of a rotating peripheral device relative to its expected position either by comparing positions or by comparing actual rotating time to expected rotating time. From this information, together with knowledge of the rotational rate, a computation of the length of time during which an I/O operation must be delayed may be made so that the actual and expected positions are in alignment upon execution of the delayed I/O operation.

14 Sheets-Sheet 12

FIG. 8

IOICB

TEBCHN X'00'	USED FOR CHAINING BLOCKS TOGETHER	
TEBTME	CONTAINS DELTA TIME WHEN BUILT, LATER CONTAINS SIMULATED TIME OF INTERRUPT	
TEBRTN	ADDRESS OF ROUTINE TO PROCESS EVENT WHEN IT OCCURS	
IOICBCW	CSW FOR I/O INTERRUPT	
CSW (CONTINUED)		
IOICBDVC	UNIT ADDRESS OF INTERRUPTING DEVICE	IOICBFB FLAGS
		NOT USED

FIG. 9a

IOOCB

(FORMAT FOR OS OPERATION FROM TRAPPED SIO)

CPCBCHN RESERVED FOR I/O SCHEDULER TO CHAIN IOICB'S TOGETHER		
NOT USED	CPCBFLGS FLAGS	NOT USED
CPCBCAW I/O PROTECT KEY	CHANNEL PROGRAM ADDRESS	
CPCBRTIM	VALUE OF REAL TIME CLOCK AT SIO-VALUE OF SIMULATED TIME CLOCK AT SIO ($E_R, SIO - E_S, SIO$)

REPOSITIONING ROTATING PERIPHERAL DEVICES

Original Filed Jan. 18, 1972

14 Sheets-Sheet 13

FIG. 9b

IOOCB

(FORMAT FOR INTERCEPTOR I/O OPERATIONS)

CPCBSENS CPCBCHN		SENSE DATA			
SENSE DATA		CPCBFLGS FLAGS	CPCBECB RELATIVE ECB NUMBER		
CPCBCAW I/O PROTECT KEY		CHANNEL PROGRAM ADDRESS			
CPCBCSW		CSW			
		CSW			
CPCBPCI NOT USED	PCI APPENDAGE ROUTINE ADDRESS (OPTIONAL)				

FIG. 10

DVCB

(DEVICE CONTROL BLOCK)

DVCBCHN X'00'	POINTER TO LCB OR IOOCB	
DVCBUNAD	UNIT ADDRESS	DVCBFLGS FLAGS
DVCBCOCB COCB POINTER	DVCBROT ROTATION TIMING POINTER	DVCBHASH HASH POINTER
BELOW IS AN ALTERNATE FORMAT OF THE DVCBCHN FIELD		
X'FF'	NOT USED	DVCBECB RELATIVE ECB NUMBER

Original Filed Jan. 18, 1972

14 Sheets-Sheet 14

FIG.11

CHCB
(CHANNEL CONTROL BLOCK)

CHCBPEND X'00'	POINTER TO 1ST PENDING IOICB		
CHCBFLGS FLAGS	CHCBSIMB CHANNEL SIMULATED BUSY	CHCBOS SIMULATED BUSY, REALLY BUSY, OS INTERRUPT EXPECTED, OS USED LAST	CHCBTPD REALLY BUSY, INTERCEPTOR USED LAST
CHCBQLEN CHANNEL QUEUE LENGTH	CHCBSM SYSTEM MASK BIT FOR CHANNEL	CHCFCUB CONTROL UNIT BLOCKAGE COUNT	
CHCBQ	CHANNEL QUEUE ENTRY NUMBER OF QUEUE ENTRIES = ONE FOR OS + ONE FOR EACH INTERCEPTOR DEVICE		

FIG.12

COCB
(CONTROL UNIT CONTROL BLOCK)

COCLBLID POINTER TO A CHAIN OF IOICB'S FOR LOCKED BID KEYS		
COCBFLGS FLAGS	COCBBASE CONTROL UNIT BASE ADDRESS	COCBFLGX FLAGS
